UNITED STATES PATENT OFFICE.

ERNEST J. LEES, OF CLEVELAND, OHIO, ASSIGNOR TO THE LEES-BRADNER COMPANY, OF CLEVELAND, OHIO, A CORPORATION OF OHIO.

THREAD-MILLING MACHINE.

1,156,237.

Specification of Letters Patent.

Patented Oct. 12, 1915.

Application filed August 27, 1913. Serial No. 786,878.

To all whom it may concern:

Be it known that I, ERNEST J. LEES, a citizen of the United States, resident of Cleveland, county of Cuyahoga, and State 5 of Ohio, have invented a new and useful Improvement in Thread-Milling Machines, of which the following is a specification, the principle of the invention being herein explained and the best mode in which I have 10 contemplated applying that principle, so as to distinguish it from other inventions.

My invention relates to machines for milling threads ordinarily referred to in the art as thread-milling machines.

15 The object of said invention is to provide a construction and arrangement of parts whereby the machine will have a maximum range of operation capable of milling threads of widely varying lead in a ready and efficient manner.

The said invention consists of means hereinafter fully described and particularly set forth in the claims.

20 The annexed drawings and the following 25 description set forth in detail certain means embodying my invention, the disclosed means, however, constituting but one of various mechanical forms in which the principle of the invention may be applied.

30 In said annexed drawings:—Figure 1 is a plan of a machine embodying my invention, shown partly in horizontal cross-section. Fig. 2 is a partial vertical longitudinal section, partly in front elevation, taken upon 35 the plane indicated by line II—II in Fig. 1, and viewed in the direction indicated by the arrows. Fig. 3 is a left-hand end elevation of the machine. Fig. 4 is a vertical transverse fragmentary section, taken upon the 40 plane indicated by line IV—IV in Fig. 8. Fig. 5 is a fragmentary vertical transverse section, upon an enlarged scale, of a detailed portion of the machine, said section being taken upon the plane indicated by line 45 V—V in Fig. 1. Fig. 6 is a vertical transverse section taken upon the plane indicated by line VI—VI in Figs. 1 or 8 and viewed in the direction indicated by the arrows therein. Fig. 7 is a front elevation of a 50 detail portion of the mechanism, illustrating part of the means for indexing the work-holding and rotating member. Fig. 8 is a rear elevation of the left-hand end of the machine with part of the housing of the 55 main driving means removed and part

broken away to disclose the said mechanism. Fig. 9 is a vertical transverse section of a fragmentary portion of the machine taken upon the plane indicated by line IX—IX in Fig. 8 and viewed in the direction indicated 60 by the arrows therein. Fig. 10 is a vertical longitudinal section of a fragmentary portion of the machine, taken upon the plane indicated by line X—X in Fig. 3.

The illustrated embodiment of my invention 65 comprises in its structure the main-frame A upon which the moving and other parts are arranged and mounted as herein-after fully described. Upon the back of the frame A is secured a suitable gear housing 70 A' in which is preferably mounted the major part of the main driving mechanism, see Fig. 8. The latter includes a main driving-shaft B upon which may be loosely mounted the main driving-pulley B'. Rotatively se- 75 cured to said shaft but longitudinally movable thereon, is a clutch-member B⁰ which is adapted to engage or disengage the pulley B'. The said pulley is provided with a suit- 80 able interior friction surface for receiving and engaging the said clutch-member. Secured upon this shaft is a gear-wheel B² which engages a pinion B³ suitably mounted in the housing A', which latter pinion en- 85 gages a gear-wheel B⁴ also similarly mount- 90 ed, all of which are preferably unchangeable. The gear B⁴ is preferably provided with an interior conical friction surface b for receiving a conical clutch-member b' forming part of a clutch B⁵ which is rota- 95 bly fixed to but slidable upon a shaft B⁶ upon which said gear B⁴ is loosely mounted. This clutch is provided with a second mem- 100 ber b² of preferably toothed formation, as shown in Fig. 10. A gear B⁷ loosely mount- 105 ed upon the shaft B⁶ is provided with a hub b⁸ which is mounted in the housing A' and the shaft B⁶ extends through the wall of the casing to the exterior, projecting from the left-hand end thereof (Fig. 1). To this 110 projecting end is detachably secured a main- driving gear B⁸. The said gear B⁷ is fur- thermore provided with a clutch-member b⁴ adapted to be engaged by the member b². By shifting the clutch B⁵, therefore, it will 115 be seen that gear B⁴ or gear B⁷ may be operatively connected with the shaft B⁶ and therefore caused respectively to drive the main driving gear B⁸ as desired. Such shifting of this clutch is effected through 110

the medium of a lever C, Figs. 4 and 10, the lower end of which articulates with an arm C' secured to a rod C² which extends toward the front of the machine and has secured thereto an operating lever C⁴, Fig. 1.

5 The clutch B⁹ is preferably operated by means of a lever B¹⁰ suitably mounted at the back of the machine, as will be readily understood from Figs. 4 and 8. Also secured 10 to the shaft B is a pinion B¹¹, Fig. 4, which through a changeable train of gears B¹², B¹³, B¹⁴ and B¹⁵, Figs. 4 and 8, is adapted also to drive the gear B⁷ and hence also the main driving-gear B⁸.

15 Gears B⁷ and B¹⁵ may remain always in place throughout all changes which may be made, but gears B¹¹, B¹², B¹³ and B¹⁴ are so mounted as to be readily removed that gears of other sizes may be substituted therefor.

20 In order to facilitate the changing of the gears in the housing A' I preferably provide the latter with a removable plate a and arrange the spindles b⁵, b⁶, Fig. 3, upon which gears B¹², B¹³ and B¹⁴ are mounted, so as to 25 be removable. Gear B¹¹ may be slipped off its spindle through an aperture a', Fig. 3, formed in the housing A'.

It will therefore be seen that this main driving-gear B⁸ may be driven by either of 30 two trains of gears each of which is driven by the driving-shaft B which is rendered operative or inoperative through the medium of the clutch B⁹. These two trains are respectively arranged so that the main driving-gear B⁸ will be driven in one direction 35 by one of said trains and in the opposite direction by the other of said trains. The direction of rotation imparted by the first described unchangeable train is such that the 40 hereinafter described feeding movement of the cutter-head will be reversed, the other and changeable train of gears driving it in its forward or operative direction.

To operate the machine, the lever B¹⁰ is 45 thrown so as to cause the driving-pulley B' to be engaged by the clutch B⁹, whereupon the main driving-shaft B rotates both the previously described trains of gears. When it is desired to obtain the reverse movement 50 of the cutter-head, the clutch B⁹ is thrown to the left, as viewed in Fig. 8, and when it is desired to effect the forward movement of said head, the said clutch is thrown to the right. It will thus be seen that in the first 55 described position of said clutch, the first described train of gears becomes operative and in the second position, the second described train of gears becomes operative, the pulley B' being driven continuously.

60 The left-hand end of the shaft B, as viewed in Fig. 8, has secured thereto a changeable gear D which meshes with a second changeable gear D' secured to the end of a head-operating shaft D², see also Figs. 1 65 and 2. This shaft extends longitudinally

along the rear of the frame and has its right-hand end, as viewed in Fig. 1, mounted in a suitable bearing A² fixed to the main frame A. The said shaft furthermore has a splined connection with a helical gear E, shown in 70 dotted lines in Fig. 1, whereby the latter may be rotated and at the same time permitted to slide along said shaft. This gear is mounted in a housing E' forming the cutter-head E³ which is arranged to slide 75 upon the frame A in a transverse direction with respect to the longitudinal axis of the machine. This cutter-head is adjustable upon a horizontal transverse axis and carries the rotating cutter E⁴ and it is driven 80 by the transverse shaft E⁵ which in turn is driven by a second helical gear E⁶, shown in dotted lines in Fig. 1, which is mounted upon said shaft, the latter having a splined connection therewith as to slide 85 therethrough. Suitable gearing connects the said shaft E⁵ with the cutter E⁴ whose axis is parallel with the longitudinal axis of the machine. The particular arrangement of 90 the cutter-head and its driving mechanism together with the feature whereby it is adjustable upon a horizontal axis, forms no part of the present invention and hence has been described only in a general way. It is 95 sufficient to merely state that the cutter E⁴ is movable in a direction transverse with respect to the axis of the machine, is movable longitudinally in both directions of said axis, and is rotatably adjustable about the axis of 100 the shaft E⁵. Suitable means, also forming no part of the present invention, are provided for moving the head E³ upon the frame, such means including a hand-wheel E⁷ and a feed-screw E⁸ connected therewith in a suitable manner.

The movement of the cutter-head in the direction of the longitudinal axis of the machine is preferably effected through the medium of a feed-screw F, Figs. 1 and 2, which 110 engages a suitable nut F' secured to the cutter-head frame E². The right-hand end of this feed-screw is journaled as at A³ and to the left-hand end of this screw is secured a gear-wheel F², Figs. 2 and 3.

Pivottally mounted upon suitable bosses 115 formed on the main frame, the lower one of which is shown in Fig. 2, are two adjustable arms G and H. The bearing end of each of these arms is preferably split and secured by means of bolts g and h respectively, (see Fig. 3). These arms may be fixed in any desired angular position upon the bearing bosses, as will be readily understood. As shown, one of these arms is mounted at the 120 upper portion of the machine and the other at its lower portion. Each arm is provided with two slots in which may be secured a train of gears, as will be understood by those skilled in the art. Another and similar adjustable arm J is mounted at this end of the 125 130

machine and also provided with a slot in which is mounted an idle gear K meshing with the main driving-gear B⁸. This idle gear K meshes with a gear h' to which is secured a pinion h², both pinion and gear being mounted in one of the slots of the adjustable arm H. Pinion h² meshes with a second gear h³ which is mounted upon a shaft h⁴ whose axis coincides with the axis 5 of adjustment of the arm H. This shaft extends through the frame A of the machine, as shown in Fig. 2, and upon its inner end is secured a pinion h⁵ which meshes with the gear F². It will therefore be seen 10 that the feed-screw F is driven through the medium of the gear train consisting of the gears K, h', pinion h², gear h³, pinion h⁵ and gear F².

Secured to the upper adjustable arm G is 20 a gear g', having a pinion g² secured thereto, and a gear g³ meshing with said pinion. The last-named pinion is secured to a shaft g⁴ whose axis coincides with the pivotal axis of the arm G. This shaft extends to the 25 right (Fig. 1) and has secured thereto a helical gear L, Fig. 6. This latter gear meshes with a second helical gear L' which is mounted upon a transverse shaft L². The front end of this shaft has secured thereto 30 a disk L⁴ which is coaxial with an outer and surrounding annular member L⁵ to which it may be adjustably secured by means of a spring-actuated pin l and a plurality of recesses l', as shown in Figs. 6 and 7. 35 The member L⁵ is fixedly secured to a rotatable hollow sleeve L⁶ which forms the bearing for the shaft L² as shown in Fig. 6. This sleeve has secured thereto a worm L⁷ which meshes with a worm-wheel L⁸. This 40 worm-wheel is secured to the live spindle L⁹ of the machine which is provided with a suitable chuck L¹⁰, Fig. 2, for holding the work. Coaxial with this work-holding device is the tail-stock M of the machine. The 45 specific construction of this work-holding and rotating means forms no part of the present invention and hence need not be further described herein, it being my intention to cover such features thereof as involve patentable novelty in a separate application for Letters Patent.

It will therefore be seen that the rotation 50 of the main driving-gear B⁸ will effect the rotation of the live work-carrying and rotating spindle L⁹ through the medium of the gear train just described. It will also be seen that the train of gears effecting such rotation is entirely independent of the train 55 of gears which effects the rotation of the feed-screw F and hence the feeding of the cutter-head E³. This characteristic of independency makes it possible to mount and compound upon each of the adjustable arms G and H, gears of widely varying diameter 60 so that a very large range of speed ratios

may be imparted to the shafts g⁴ and h⁴. This means that widely varying relationships may be established between the movement of the cutter-head and the rotation of the work, thus permitting threads of widely 70 varying lead to be cut upon this machine by the simple substitution and compounding of gears on the adjustable arms, as will be readily understood by those skilled in the art. Furthermore the required speed of return movement may be obtained by changing the gear B⁸ to one of required diameter, as will be understood. Should this change, however, result in too great or too slow a speed of rotation of the work, then other 75 and required gears may be substituted for the changeable gears B¹¹, B¹², B¹³ and B¹⁴, so as to either retard or accelerate the speed of gear rotation of B⁸. It will hence be observed that the required speed of return 80 and speed of rotation of the work can be obtained without disturbing the relation of rotation of the work to the lead of the cutter-head. In addition to this, the required speed of rotation of the cutter itself may 85 be obtained independently by adopting gears of proper diameter for the gears D and D'.

The idler K is preferably provided in order to impart the correct direction of movement of the cutter-head as may be required when certain combinations of gears are used. Under certain conditions this gear is entirely omitted and arm H is swung upwardly so as to cause gear h' to mesh directly with gear B⁸.

In order to punctuate the positions of the clutch-operating lever C⁴ and accurately determine the positions thereof which effect the forward and reverse movements of the 105 gear trains and which will also enable the operator to throw the lever into neutral position in which the rotation of these trains is interrupted, I provide a segment N, Figs. 1 and 5, provided with three notches n, n' 110 and n². The lever C⁴ carries a spring-actuated pin c having a beveled extremity, which engages these notches, the latter being arranged at distances from each other such as to engage the said pin when the required positions of the clutch B⁵ are obtained. As shown, this lever may also be secured to a rod O provided with stops o, o', engaged by a suitable extension e secured to the cutter-head frame, Fig. 1. When the cutter-head is moving toward the head-stock, extension e will engage stop o and the lever C⁴ will be thrown over to the left into neutral position where pin c engages notch n', when all work rotation and lead movement 120 ceases. The operator now disengages the cutter from the work and throws lever C⁴ to the left, thus causing the quick-return train of gears to become operative. This quick-return movement proceeds until the stop o 125

is engaged by extension *e* and the lever is brought back into neutral position. The operator now properly sets the cutter to assume the cutting position and then throws the lever *C*⁴ to the right, thus initiating the operative movement of the cutter-head.

To those skilled in the art of making apparatus of the class described, many alterations in construction and widely differing embodiments and applications of my invention will suggest themselves without departing from the spirit and scope thereof as set forth in the claims. My disclosures and description herein are purely illustrative and are not intended to be in any sense limiting.

Having fully described my invention, what I claim and desire to secure by Letters Patent is:—

1. In a machine of the character described, the combination with a frame, a cutter carrying head mounted to slide longitudinally in opposite directions on said frame, a rotary work holder and a drive member, of a driven member, connections between said driven member and said head and between said driven member and said work holder for operating said head and said work holder in either direction accordingly as said driven member is operated, gearing connected with said drive member and arranged to rotate said driven member in one direction, separate gearing connected with said drive member and arranged to rotate the driven member in the opposite direction, and means for connecting either of said gearing to said driven member.

2. In a machine of the character described, the combination with a frame, a cutter carrying head mounted to slide longitudinally in opposite directions on said frame, a rotary work holder and drive member, of a driven member, connections between said driven member and said head and between said driven member and said work holder for operating said head and said work holder in either direction accordingly as said driven member is operated, gearing connected with said drive member and arranged to rotate said driven member in one direction, separate gearing having a power transmitting ratio different from the first mentioned gearing and connected with said drive member and arranged to rotate the driven member in the opposite direction, and means for connecting either of said gearing to said driven member.

3. In a machine of the character described, the combination with a frame, a cutter carrying head mounted to slide longitudinally in opposite directions on said frame, a rotary work holder and a drive member, of a driven member, connections between said driven member and said head and between said driven member and said work holder for operating said head and

said work holder in either direction accordingly as said driven member is operated, gearing connected with said drive member and arranged to rotate said driven member in one direction, separate gearing connected with said drive member and arranged to rotate the driven member in the opposite direction, and means for connecting either of said gearing to said driven member, the elements constituting the gearing for rotating the driven member in one direction being changeable.

4. In a machine of the character described, the combination with a frame, a cutter carrying head mounted to slide longitudinally in opposite directions on said frame, a rotary work holder and a drive member, of a detachable driven member, connections between said driven member and said head and between said driven member and said work holder for operating said head and said work holder in either direction accordingly as said driven member is operated, gearing connected with said drive member and arranged to rotate said driven member in one direction, separate gearing connected with said drive member and arranged to rotate the driven member in the opposite direction, and means for connecting either of said gearing to said driven member, the elements constituting the gearing for rotating the driven member in one direction being changeable.

5. In a machine of the character described, the combination with a frame, a cutter carrying head mounted to slide longitudinally in opposite directions on said frame, a rotary work holder and a drive member, of a driven member, connections between said driven member and said head and between said driven member and said work holder for operating said head and said work holder in either direction accordingly as said driven member is operated, gearing connected with said drive member and arranged to rotate said driven member in one direction, separate gearing connected with said drive member and arranged to rotate the driven member in the opposite direction, and means for connecting either of said gearing to said driven member, the elements constituting the gearing for rotating the driven member in one direction being changeable.

6. In a machine of the character described, the combination with a frame, a cutter carrying head mounted to slide longitudinally in opposite directions on said frame, a rotary work holder and a drive member, of a driven member, connections between said driven member and said head and between said driven member and said work holder for operating said head and said work holder in either direction accordingly as said driven member is operated, gearing connected with said drive member and ar-

ranged to rotate said driven member in one direction, separate gearing having a power transmitting ratio different from the first mentioned gearing and connected with said 5 drive member and arranged to rotate the driven member in the opposite direction, and means for connecting either of said gearing to said driven member, the elements constituting the separate gearing being changeable.

7. In a machine of the character described, the combination with a frame, a cutter carrying head mounted to reciprocate on said frame, a rotatable work holder and 15 a drive member, of a driven member, drive connections between said driven member and said head for reciprocating said head, separate drive connections between said driven member and said work holder for rotating it in coöperation with the movement of said head, and means between said drive member and said driven member for rotating the latter in opposite directions.

8. In a machine of the character described, the combination with a frame, a cutter carrying head mounted to reciprocate on said frame, a rotatable work holder and a drive member, of a detachable driven member, drive connections between said 25 driven member and said head for reciprocating said head, separate drive connections between said driven member and said work holder for rotating it in coöperation with the movement of said head, and means between said 30 driven member and said driven member for rotating the latter in opposite directions.

9. In a machine of the character described, the combination with a frame, a cutter carrying head mounted to reciprocate on 40 said frame, a rotatable work holder and a drive member, of a driven member, drive connections between said driven member and said head for reciprocating said head, 45 separate drive connections between said

driven member and said work holder for rotating it in coöperation with the movement of said head, and means between said drive member and said driven member for rotating the latter in opposite directions, said 50 means having changeable elements, whereby the speed of the driven member can be changed when rotated in one direction.

10. In a machine of the character described, the combination with a frame, a cutter carrying head mounted to reciprocate on said frame, a rotatable work holder and a drive member, of a driven member, drive connections between said driven member and said head for reciprocating said head, 55 separate drive connections between said driven member and said work holder for rotating it in coöperation with the movement of said head, and means between said drive member and said driven member for rotating the latter in opposite directions, each of 60 said drive connections including changeable gears.

11. In a machine of the character described, the combination with a frame, a cutter carrying head mounted to reciprocate on said frame, a rotatable work holder and a drive member, of a driven member, drive connections between said driven member and said head for reciprocating said head, 70 separate drive connections between said driven member and said work holder for rotating the latter in coöperation with the movement of said head, and means between said drive member and said driven member for rotating the latter in opposite directions, each of 75 said drive connections including changeable gears and adjustable devices for supporting the changeable gears in coöoperative relationship.

Signed by me, this 11th day of Aug., 1913.
ERNEST J. LEES.
